UNITED STATES PATENT OFFICE.

WILLIAM BLANCHARD, OF BOSTON, MASSACHUSETTS.

WINDOW SHADE.

Application filed May 21, 1923. Serial No. 640,458.

To all whom it may concern:

Be it known that I, WILLIAM BLANCHARD, a citizen of the United States, residing at Boston, in the county of Suffolk and State of Massachusetts, have invented new and useful Improvements in Window Shades, of which the following is a specification.

This invention relates to improvements in shade fixtures particularly adapted for use with windows having swinging sash.

An object of the invention is to provide a fixture mounting a shade for movement toward or away from the window so that when the sash are swung open the shade may be moved away from the window a sufficient distance to clear the sash when it is lowered.

Another object of the invention is to provide a movable mounting for a shade roller with means for guiding the free end of the shade and means for moving the shade toward or away from a window.

Other objects reside in the details of construction and cooperation of the parts which are clearly pointed out in the following description and claims and shown in the accompanying drawings in which,

Figure 1 is a sectional view through a window using swinging sash with the shade fixture shown in cooperation therewith and the shade drawn,

Figure 2 is a detail elevation of the shade fixture constructed according to this invention,

Figure 3 is a detail elevation at right angles to Figure 2 showing the shade fixture and shade in position, and

Figure 4 is a detail view of the bracket for guiding the operating cables.

A window sash is generally indicated at 1 having swinging sections 2 mounted on horizontal pivots as clearly shown in Figure 1.

Inclined track bars 3 are secured to the ceiling adjacent the window frame through terminal extensions 4 and movably receive shade roller carrying members 5 provided with rollers 6 riding on the track bars. The members 5 have depending roller holders 7 pivotally mounted thereto at 8 and detachably receiving the shaft 9 of the shade roller through the clamp connection 10. Guide members 11 have one end secured to the clamping portions 10 of the roller holders and the other ends passed through eye

bolts 12 mounted below the window and secured to spring members 13 fastened to the floor as indicated at 14. This resilient connection of the guide members permits the free movement of the roller holding members on the track bars. The natural tendency of the roller holding members is to assume a position away from the window as indicated in dotted line at 15 in Figure 2 due to the inclination of the track bars.

Operating cables 16 are connected with the roller holding members 5 and guided over pulleys 17 and 18 mounted on bracket 19 removably secured to the terminal extension 4 adjacent the window frame, the cables terminating in a single operating member 20 depending to the lower end of the window 75 where it may be connected with any suitable operating means generally indicated at 21 which will draw the roller holding members up the inclined track ways to position the shade close to the window which is 80 desirable when the swinging sash are in closed position.

The free edge of the shade 22 is provided with a cross-bar 23 having terminal eyes 24 receiving the guiding members 11 for guiding the shade as it is raised and lowered and for preventing the same from flapping.

It will be seen from the above that a simple shade fixture is provided for use with swinging sash to permit the drawing of the shade when the sash are opened without interfering with said sash and which will hold the shade in any desired position with relation to the window and which may be operated to draw the shade into close proximity with the window when the sash are closed.

The terminal portions of the shaft 9 of the shade roller are each provided with a pair of spaced circumferential disks 25 between which the free end of tape 26 is attached for raising the shade. The lowering of the shade causes the tape to wind on the shaft 9 between the disks 25. To raise the shade it is only necessary to unwind the tape, the shade being maintained in elevated position by tying or hooking the tape to some portion of the window or wall structure, which has not been illustrated.

While the invention has been disclosed in concrete form, yet various changes and modifications may be made therein without de-

parting from the spirit of my invention, the scope of which is defined by the following claims.

What is claimed is:

- 5 1. The combination with a pair of inclined tracks having upwardly directed terminal portions adapted for attaching the tracks to a ceiling, carriages mounted on said inclined tracks, holders pivotally suspended from said carriages, a roller having pintles connected to said holders, flexible elements connected to said holders and adapted for securing the holders in an adjusted position, guide rods connected to said holders, contractile springs connected to the lower ends of the guide rods, a shade connected to said rollers and having eyelets receiving said guide rods, and lengths of tape connected to said rollers adjacent the ends thereof and forming a means whereby to adjust said shade.
- 10 10 from said carriages, a roller having pintles connected to said holders, flexible elements connected to said holders and adapted for securing the holders in an adjusted position, guide rods connected to said holders, contractile springs connected to the lower ends of the guide rods, and a shade connected to said rollers and having eyelets receiving said guide rods.
- 15 2. The combination with a pair of inclined

tracks having upwardly directed terminal portions adapted for attaching the tracks to a ceiling, carriages mounted on said inclined tracks, holders pivotally suspended from said carriages, a roller having pintles connected to said holders, flexible elements connected to said holders and adapted for securing the holders in an adjusted position, guide rods connected to said holders, contractile springs connected to the lower ends of the guide rods, a shade connected to said rollers and having eyelets receiving said guide rods, and lengths of tape connected to said rollers adjacent the ends thereof and forming a means whereby to adjust said shade.

In testimony whereof I affix my signature.

WILLIAM BLANCHARD.
